SYNCHRONIZED CLOCK ESCAPEMENT

Julius W. Hansen, William L. Hansen, and Ira N. Hurst, Princeton, Ind., assignors to Hansen Manufacturing Company, Inc., Princeton, Ind., a corporation of Indiana

Application November 3, 1930, Serial No. 492,920

15 Claims. (Cl. 58—26)

This invention relates to clock escapements which are electrically synchronized to the ordinary commercial alternating electric current.

A distinction should be made between the term "synchronized" and the term "synchronous". The latter term is commonly used with reference to a synchronous motor with a reduction gear for operating clocks. Such a synchronous clock is driven by a synchronous motor

10 and contains neither a spring motor nor an escapement, nor a hair spring balance wheel nor a pendulum. The clock of the present invention, however, is driven by a spring motor which may be either hand or electrically wound. The present invention may be applied either to a pendulum clock or to what is known as a marine clock, namely, one having a balance wheel and hair spring, to which latter type the ordinary pocket watch belongs.

20 One object of the present invention is therefore to synchronize and regulate the ordinary clock by means of an alternating current which, however, does not furnish motive power to drive it. For the purpose of the present invention it is only necessary to substitute a special balance wheel in the case of a marine clock, and a special pendulum in the case of a pendulum clock for these parts as ordinarily found in clocks. The essential problem is to ascertain the distance the periphery of the balance wheel travels in one second and supply this distance with 120 pole projections in the case of a sixty-cycle current, since there are 120 alternations in such current.

30 What has been said in regard to balance wheels also applies to pendulum clocks. In this form of clock the oscillation is effected by a pendulum rather than by a balance wheel, and a similar arrangement of poles is necessary, these poles being located at some suitable point near the lower end of the pendulum.

It is another object of this invention to provide a time-piece that is not entirely dependent on electric current for operation, and that will 45 still continue to run and keep time even when the current is off. Since the current interruptions are usually of very short duration, it is evident that this feature is valuable and makes such a time-piece dependable since the variation of the clock is very small during the short period it is without the synchronizing effect of the current.

For the purpose of illustrating the invention there is shown in the accompanying forms a preferred embodiment of the synchronized self-

driving clock of the present invention with its regulating, synchronizing mechanism.

Referring to the drawings:

Figure 1 shows a side elevation of a balance wheel and the escapement associated therewith. 5

Figure 2 shows a top plan view of the clock parts shown in Figure 1.

Figure 3 shows a modified form of balance wheel control.

Figure 4 shows a front elevation of the lower 10 end of a pendulum adapted to be used in connection with a clock control of this type.

Figure 5 shows a side elevation of the form shown in Figure 4.

Figure 6 shows a slightly modified form of 15 balance wheel and the control magnet operating therewith.

Referring to the drawings in detail, Figures 1, 2 and 3 show the present invention as applied to 20 clocks with a balance wheel 1 and escapement 20 control mechanism supported by a frame A of any suitable material, usually brass or the like.

The balance wheel 1 is carried by a shaft 2 suitably supported by the frame A so that the balance wheel 1 may freely oscillate about the 25 support of the shaft 2. On one end of the shaft 2 adjacent one part of the frame is a hair spring 3, which has one end attached by some suitable means to the shaft 2 while the other end is attached to a stud 4 projecting from one part of 30 the frame. This hair spring 3 is of the type usually found in watches and clocks.

On the balance wheel 1 and disposed diametrically opposite one another are two groups of 35 projections of magnetic material. In one group the projections are numbered 5, 5a, 5b, 5c and 5d. In the other group the projections are numbered 6, 6a, 6b, 6c, and 6d. The projections of the respective groups are so arranged that the projections 5 and 6, 5a and 6a, 5b and 6b, 5c and 6c and 5d and 6d are opposite one another, with 40 a greater space intervening between the two groups than between the individual projections within each group.

Disposed adjacent the respective groups of 45 projections and in line with a diameter through the balance wheel shaft 2 are the oppositely arranged magnet pole members 19 and 20 at the opposite ends of the magnet 18. The latter is encircled by the energizing coil 21. The above-mentioned projections are so spaced apart that in the oscillation of the balance wheel 1 the movement of one projection from one position to the position of its next adjacent projection takes place during the time that the change in 55

magnetism takes place in an adjacent magnetic pole 19 or 20.

Let it be assumed that the balance wheel 1 as shown in Figure 1 is moving in a clockwise direction and that the coil 21 is energized by alternating current electricity. The magnetism of the pole 19 magnetizes the projection 5c on the balance wheel adjacent the pole 19 and attracts the projection toward it. At the time this projection reaches the position opposite the pole a current passing through the coil 21 will have changed direction so that the pole 19 is differently magnetized, thereby repelling the projection 5c and bringing opposite the pole 19 the projection 5d, which has become magnetized by its presence adjacent the pole 19.

By the time the projection 5d reaches the position opposite the pole 19 the direction of the current in the coil 21 again changes and differently magnetizes the pole 19 so that the projection is repelled and another one attracted. This continues until the space between the projection 5d and 6b is reached, at which time no part of the balance wheel 1 is magnetized whereupon the coil spring 3 reverses the direction of oscillation of the balance wheel 1. Then the opposite action of the magnet takes place and causes the balance wheel to rotate in an anti-clockwise direction by successively magnetizing, attracting and repelling the different projections.

While we have mentioned only the projections moving adjacent the pole 19, the same results and actions are meanwhile taking place in the opposite projections 6, 6a, 6b, 6c and 6d adjacent the pole 20. The poles 19 and 20 are oppositely magnetized when the coil 21 is energized and cooperate with each other in controlling the oscillation of the balance wheel.

Extending from one side of the balance wheel 40 is a stud or projection 7 adapted to engage one end of an escapement lever 11. At the opposite end of the escapement lever 11 is an escapement wheel 8, which is mounted upon a shaft 9 pivoted in the frame A and has the usual teeth 10. The escapement lever 11 is pivotally supported by the shaft 12 in the frame A. The end of the lever 11 adjacent the escapement wheel shaft 9 is curved to form two arms 13, which straddle the shaft 9 as shown in Figure 1.

Extending from the shaft 12 and in the direction of the teeth 10 of the wheel 8 are oppositely disposed escapement prongs 14 and 15. These two prongs constitute the escapement part of the escapement lever 11, and are adapted to alternately engage the teeth 10 during the operation of the clock mechanism. On the end of the escapement arm remote from the curved arms 13 is a head 16 having seats 17 adapted to be engaged by the stud 7 in the oscillation of the balance wheel 1.

The power, from whatever source it is derived, is connected to the shaft 8 in some suitable manner so that the escapement wheel 8 is caused to move in one direction and is controlled in that movement by the operation of the escapement lever 11, which is controlled in its movement by the oscillating wheel or balance wheel 1. The structure so far described is substantially that found in marine clocks.

Associated with the balance wheel is a magnet 18 in the shape of a U or horse shoe, the ends 19 and 20 of which serve as magnet poles and have placed between them the oscillating balance wheel 1. The free ends of the magnet 75 are thus curved toward each other so that peri-

odically the projections on the balance wheel 1 pass adjacent the free ends of the arms of the magnet. Coiled around the magnet is the previously mentioned energizing coil 21 which is connected to some source of alternating current of electricity. In the operation of the clock of Figures 1 and 2, as the current of electricity passes through this coil the poles 19 and 20 of the magnet 18 are oppositely magnetized and the magnetization of these poles causes the projections on the balance wheel 1 to become magnetized so that they are alternately drawn and repelled, due to the rapid successive changes in the magnetization of the different poles. This action has been previously described.

In Figure 3 there is shown a slightly modified form of magnetic control for the oscillating balance wheel. In this form instead of having the groups of projections on the balance wheel the projections are arranged in groups on the magnet. In this form the magnet 22 has a coil 23 and poles 24 and 25, similar to the poles shown in Figure 1, with the exception that in this form the outer ends of the poles are arch shaped to correspond to the curvature of the periphery of the balance wheel 26, and have projections projecting inwardly toward the balance wheel projections 27 and 28. On the pole 24 the inwardly directing projections are indicated by 24a, 24b, 24c, 24d and 24e, while the projections on the pole 25, which is shaped similarly to pole 24, are indicated by 25a, 25b, 25c, 25d and 25e.

In this form the balance wheel 26 has only two projections, 27 and 28, which are arranged opposite each other. The current passing through the coil 23 oppositely magnetizes poles 24 and 25. When the pole 24 is positively magnetized the projection 27 is negatively magnetized. The pole 25 is negatively magnetized, while the projection 28 is positively magnetized.

Since the balance wheel 26 is oscillating, due to the action of the spring, similar to that shown in Figure 1, the projections 27 and 28 move away from the projections presently adjacent to them, and while they are thus moving the current shifts so that the magnetization of the poles 24 and 25 changes, the pole 24 becoming negative and the pole 25 becoming positive. This magnetization of the poles repels the projections 27 and 28, after which they become magnetized oppositely to their previous magnetization and are attracted by the projections 24b and 25b. This action continues until the projection 27 passes beyond the projection 24c and the projection 28 passes beyond the projection 25c.

By this time the energy stored up in the spring has become sufficiently great that the reverse action of the balance wheel takes place, and the projection 27 moves successively past the projections 24c, 24b until the projection 27 passes the projection 24e. When the magnetization of the projections 27 and 28 again ceases the reverse rotation of the balance wheel takes place, due to the opposite accumulation of force in the hair spring.

The parts are so arranged that the movement of the projection 27 from one projection on the pole to another projection on the pole takes place in the time required for the change in alternation of the alternating current through the coil 23, and a consequent change in the magnetization of the projections on the poles 24 and 25. In other words, the period of time required for the projection 27 to move from the projection 24e around to the projection 24c is two complete alternations.

It is therefore obvious that if the parts are properly constructed and a current with the proper period of alternation is used, the timing of the clock movement is duly controlled, even though the clock is driven independently, as by a pendulum or spring.

In Figures 4 and 5 there is shown a pendulum adapted to be used in connection with applicant's electro-magnetic control. In this form the pendulum rod 29, has a bob 30 which is arcuate in shape and has extending therefrom, in opposite directions, projections 31 and 32. The projections 31 extend upwardly, while the projections 32 extend downwardly, as indicated in Figure 4.

In Figure 5 there is shown a magnet 33 which has poles 34 and 35. This magnet is in the form of a shoe and has around the central part thereof a coil 36 for receiving an alternating electric current. The magnetization effected in this form is similar to that in the other forms. Instead of operating upon a balance wheel in the present instance the poles operate upon projections on a pendulum. The action and principles of action are in all senses the same. In this case they control the oscillation of the pendulum, while in the other two forms of the invention the control is applied to the oscillation of a balance wheel.

The balance wheels 1 and 26 and the pendulum bob 30 and the projections on the pendulum bob are made of some magnetic material, such as soft iron, and the magnets are of the same material.

In the form shown in Figure 6 the balance wheel 37 is made of some non-magnetic material and has recesses 38 at diametrically opposite points in its periphery. In one of these recesses is mounted a soft iron plug 39, which has extending radially therefrom a plurality of projections. The central projection 40 has spaced equally therefrom two projections 40a and 40c.

Equally spaced from these two projections 40a and 40c are projections 40b and 40d. The space between the projections 40a and 40b is equal to the space between the projections 40c and 40d. Likewise, the spaces between the projections 40 and 40c, and 40 and 40a are equal. These projections are thus arranged because as the balance wheel approaches the end of its period of oscillation its speed of movement is retarded, and by the arrangement of the projections as here described, the periods of time between which one projection and the succeeding projection pass in front of one of the magnet poles are the same.

In the other of the recesses 38 is mounted a non-magnetic plug 41. This plug is of the same weight as the plug 39 so that the balance wheel is maintained in a balanced condition. This plug 41 may have projections therefrom similar to the projections on the plug 39. However, these plugs may be omitted, the object in either case being that the plug 41 be of the same weight as the plug 39.

Adjacent the plug 39 is a horse shoe magnet 42, which has pole pieces 43 and 44. Around the part of the magnet intermediate the poles is a coil 45 connected to some source of alternating electric current. When the current is passing through the wires of the coil the poles are alternately and oppositely magnetized. In thus magnetizing the poles a magnetic flux 46 is produced, which alternates through the poles and produces an alternating magnetic flux in the projections opposite the poles. The line of magnetic flux, as shown in Figure 6, may be followed not only through the poles but through the core and the projections thereon adjacent the ends of the poles 43 and 44.

The action in this form is the same as that in the others, the difference being that in this form the projections are arranged successively closer one to the other beginning with the middle projection, and these projections are formed on a separate piece of soft iron suitably fitted in one part of the periphery of the balance wheel. The arrangement of the projections is for the purpose of making the time between the passing of one projection in front of a pole and adjacent projection the same for all points in the period of oscillation of the balance wheel. In this form the usual hair spring is used for providing the energy for oscillating the balance wheel.

We desire to comprehend within our invention such modifications as may be embraced within our claims and the scope of our invention.

Having thus fully described our invention, what we claim is new and desire to secure by Letters Patent, is:

1. In a clock mechanism, an oscillating member having a plurality of pairs of oppositely disposed projections, a source of an alternating electric current, and means acted upon by said current to alternately attract and repel successively each pair of projections.

2. In a clock mechanism, an oscillating member having a plurality of pairs of oppositely disposed projections, a source of an alternating electric current, a magnet having an arm on each side of said oscillating member, and means acted upon by said current to alternately and oppositely magnetize said arms to alternately attract and repel successively the projections of each pair of projections as the oscillating member oscillates.

3. In a clock mechanism, a rotating member and means to control the speed of rotation of said rotating member, said means comprising an oscillating member having oppositely disposed groups of projections thereon, and means acting in regular periodic succession to attract and repel in succession the projections of each group.

4. In a clock mechanism, a rotating member, an oscillating member to control the speed of rotation of said rotating member, said oscillating member having a pair of groups of projections, and magnetic means acting in regular periodic succession to successively magnetize, attract and repel successively each projection of each group to determine the period of oscillation in one direction.

5. In a clock mechanism, an oscillating member of non-magnetic material, a plurality of magnetic projections from one side of said oscillating member, means to cause said member to oscillate, a magnetic member adjacent said projections, and means to cause a variation of magnetic flux in said magnetic member whereby the period of oscillation of the oscillating member is maintained uniform.

6. In a clock mechanism, a balance wheel of non-magnetic material having in one part a plug of non-magnetic material and an oppositely disposed plug of magnetic material, said last plug having projections thereon, a U-shaped magnetic member with its ends disposed adjacent said projections, and means to cause an alternating magnetic flux in said magnetic member.

7. In a clock mechanism, an oscillating wheel of non-magnetic material having on its periphery a plug of magnetic material, said plug having projections thereon, a U-shaped magnetic member with its ends adjacent said projections, and a coil around the central part of said magnetic member whereby the ends of said magnetic mem-

- ber are alternately oppositely magnetized to regulate the oscillation of said wheel.
8. In a clock mechanism, a balance wheel of non-magnetic material having on one part of its periphery a plug of magnetic material, said plug having spaced projections thereon, the spaces between the projections uniformly decreasing from the central projection to the end projections, means to cause the wheel to oscillate, a looped magnet having its ends adjacent the projections, and means to successively alternately magnetize the ends of the magnet and the projections on the wheel.
9. In a balance-wheel-escapement clock mechanism, a balance wheel having poles, means to drive said balance wheel, and means in circuit with a source of alternating current adapted to electrically influence the movement of said balance wheel to bring its movements in harmony with the alternations of current in said circuit.
10. In a balance-wheel-escapement clock mechanism, a balance wheel having poles, means to drive said balance wheel, and means in circuit with a source of alternating current adapted to electrically influence the movement of said balance wheel to bring its movement in harmony with the alternations of current in said circuit, said second-named means comprising an electromagnet.
11. In a balance-wheel-escapement clock mechanism, a balance wheel having poles, means to drive said balance wheel, and means connected to an alternating-current circuit associated with said balance wheel and adapted to bring its movements into synchronism with the alternations of current in said circuit.
12. In a balance-wheel-escapement clock mechanism, a balance wheel having poles, means to

drive said balance wheel, a synchronizing means having poles associated with the poles of the balance wheel but spaced therefrom, and an alternating current circuit associated with said synchronizing means whereby the movement of the balance wheel will be synchronized with the alternations of the current in the circuit.

13. In a balance-wheel-escapement clock mechanism, a balance wheel having poles, means to drive said balance wheel, a synchronizing means having poles associated with the poles of the balance wheel but spaced therefrom, and an alternating current circuit associated with said synchronizing means whereby the movement of the balance wheel will be synchronized with the alternations of the current in the circuit, said synchronizing means comprising an electro-magnet.

14. In a balance-wheel-escapement clock mechanism, a balance wheel in said clock, said wheel having projections thereon, means to drive said balance wheel and means connected to an alternating current circuit adapted to regulate the movements of said balance wheel and synchronize them in harmony with the alternations of the current in said circuit by successively magnetizing, attracting and repelling each projection.

15. In combination, an escapement, an escape-
ment lever, a balance wheel, a hair spring, said
balance wheel having a plurality of projections,
an electro-magnet having oppositely-disposed
poles adjacent said projections successively, and
a source of alternating current connected there-
with.
